US00D980591S

(12) United States Design Patent (10) Patent No.: US D980,591 S
(45) Date of Patent: * Mar. 14, 2023

(54) SHOE

(71) Applicant: STARLINK TECHNOLOGY CO., LIMITED, Hong Kong (CN)

(72) Inventor: Jie Huang, Singapore (SG)

(73) Assignee: STARLINK TECHNOLOGY CO., LIMITED, Hong Kong (CN)

() Term: 15 Years

(21) Appl. No.: 29/810,963

(22) Filed: Oct. 11, 2021

(51) LOC (14) Cl. 02-04

(52) U.S. Cl.

USPC D2/926; D2/918

(58) Field of Classification Search

USPC D2/896, 950, 919, 916, 929, 930, 940,
D2/942, 943

See application file for complete search history.
